Primary Examiner — Rachel A. Voorhies*Assistant Examiner* — Benjamin D. Wannemacher(74) *Attorney, Agent, or Firm* — Lambert Shortell & Connaughton; David J. Connaughton, Jr.; Justin P. Tinger(57) **CLAIM**

The ornamental design for a curtain spacer, as shown and described.

DESCRIPTION

FIG. 1 is a perspective view of the curtain spacer, which embodies my design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

Portions of the drawings shown in broken lines illustrate portions of the curtain spacer and form no part of the claimed design.
